MAGNETO

Kenneth A. Harmon, Longmeadow, Mass., assignor to Wico Electric Company, West Springfield, Mass., a corporation of Massachusetts

Application October 22, 1937, Serial No. 170,403

2 Claims. (Cl. 171—209)

This invention relates to improvements in high tension magnetos, such as are suitable for use as an ignition means for multi-cylinder internal combustion engines.

5 The general object of the invention is to provide in a high tension magneto an improved arrangement of parts, characterized by compactness and enabling the magneto to be made small in size and at the same time powerful and efficient.

10 The invention, for example, enables the magneto to be of such small dimensions that it may be mounted on and driven from the internal combustion engine in the same manner as the timer-distributer units now employed with the battery ignition systems of automobiles.

15 Another object of the invention is to provide a high tension magneto, in which the stator is composed of a plurality of coils and cores mounted in a circular series around the magneto drive shaft 20 with the axes of coils, cores and shaft in substantially parallel relation, and in which the rotor, driven by the shaft, is composed of at least one and preferably two multi-polar magnets of high coercive force and very small size, one magnet being located above and cooperating with the upper ends of the cores and the other being located below and cooperating with the lower ends of the cores.

25 A further object of the invention is to provide a high tension magneto which is designed for manufacture in quantities at low unit cost.

30 Other objects will appear as the detailed description proceeds and will be pointed out in the appended claims.

35 The invention will be disclosed with reference to the accompanying drawings, in which:

Fig. 1 is a full size, sectional elevational view of a magneto embodying the invention;

30 Figs. 2, 3 and 4 are cross sectional views taken on the lines 2—2, 3—3, and 4—4, respectively, of Fig. 1;

Fig. 5 is a cross sectional view taken on the line 5—5 of Fig. 1, showing the timer mechanism;

Fig. 6 is a fragmentary sectional view taken on the line 6—6 of Fig. 2;

Fig. 7 is a fragmentary exterior elevational view with parts broken away to show the mounting of the cores;

Fig. 8 is a fragmentary sectional elevational view taken on the line 8—8 of Fig. 2; and

Fig. 9 is a wiring diagram showing the electrical connections.

Referring to these drawings: the magneto has been illustrated as of the so-called timer type, 55 having on the bottom part of its casing (Fig. 1)

a sleeve 10 adapted to fit in a socket of an internal combustion engine in the same manner as the usual timer-distributer unit used in battery ignition systems. The driving shaft 11 has a bearing in this sleeve and extends below it carrying an 5 element 12 for coupling engagement with a shaft of the engine. The magneto casing has a seat 13 which is adapted to rest on and be supported by the end face of said socket. The sleeve 10 is held in such socket by suitable means (not shown), 10 engaging in the circumferential groove 14 of sleeve 10.

The magneto casing is constructed in three generally cylindrical sections 15, 16 and 17, mounted one upon the other in superposed and 15 also in coaxial relation. Usually the upper section 17 carries a distributor cap 18, made of insulating material and mounted on section 17 for convenient removal in any of the usual and well known ways. The sections 15 and 17 which may 20 be made of iron or other metal or any other suitable material, have annular flanges such as 19 to fit into and engage the cylindrical outer wall of the intervening section 16, whereby the several sections are centralized one with another. These 25 three sections are firmly held together by a series of cap screws 20 (Fig. 6), which pass through sections 15 and 16 and thread into section 17.

The middle section 16 is advantageously made of bakelite or similar material, molded in the 30 form shown. It has a lower end wall 21 and, standing centrally therefrom, a sleeve 22 in the upper end of which is inserted a bearing 23 for shaft 11. The upper end of sleeve 22 and the upper end of the outer cylindrical wall of casing 35 section 16 are formed with seats, upon which rests a top closure plate 24 of annular form,—such plate being preferably also made of bakelite. The parts 16, 21, 22 and 24 form a closed annular chamber in which all the coils of the magneto 40 are housed. The cores for these coils, as well as other non-coil-carrying cores pass through this chamber and have their ends projecting slightly above the top wall 24 and slightly below the bottom wall 21.

45 Referring to Fig. 4, the cores and coils are arranged in a circular series. There are a plurality, eight in this case, of cores 25 spaced at equal angular intervals around shaft 11 and at equal radial distances therefrom. Alternate cores 50 of the series carry coil units,—each such unit comprising a primary coil 26 and a secondary coil 27. As will be seen from Fig. 1, the axes of these cores and coils parallel the axis of shaft 11. The cores may be fixed in their housing in any suitable way. 55

One desirable way is to make that portion of each core, which lies between the end walls 21 and 24; slightly wider than the portions of the core that pass through said walls. For example, the two outer laminations of each core may be made shorter as shown in Figs. 6 and 7, whereby shoulders 28 are formed. The walls 21 and 24 are formed with holes to fit the ends of the cores and the shoulders abut the inner faces of the two end walls. Then, when the cap screws 20 are tightened, the flange 19 of section 17 will press the top wall 24 against the upper shoulder 28 of each core 25 and force these cores downwardly until the lower shoulder 28 of each engages the bottom wall 24.

Also located within the casing section 16 is a high tension conductor in the form of a circular band of metal 29 (Fig. 1) which is slipped into the coil housing from its upper end and pressed downwardly until it seats on a shoulder formed on the inner wall of section 16. This band has struck out therefrom at suitably spaced intervals, spring fingers 30 adapted to engage, one with each, the high tension terminals 31 of the secondary coils. The section 16 is formed with an integral upstanding socket 32 (Fig. 8) to receive a high tension conductor and within the socket is a metal part 33 with which said conductor is adapted to make contact. A spring 34 connects part 33 with the band 29.

In assembling the parts the lower ends of the cores 25 are set into the holes in wall 21; the coils 26 and 27 are slipped over the proper cores; the necessary electrical connections are made; then the space within the coil housing is filled with wax or other suitable material; and the cover 24 is applied. This complete unit is then slipped over the shaft, which has been previously mounted in section 15 and onto its seat on the latter. The cap screws 20 are then applied to clamp the casing sections together.

The rotors are permanent magnets suitably fixed to shaft 11. The latter has a shoulder 36 to engage a seat formed on the inner face of the bottom wall of section 15. This shoulder 36 and a collar 37, fixed to shaft 11 just below the lower end of sleeve 10, hold the shaft in position axially. The magnets are made of special steel of such a class that very high coercive force can be obtained from magnets of very small dimensions. The magnetic rotors, as herein shown, are formed by casting. Each has as many arms 38 as there are cores, alternate arms being of opposite polarity (Figs. 2 and 3). The arrangement provides the equivalent of a circular series of horseshoe magnets (four in this case) having the inner ends interconnected. The neutral points of each magnet lie nearest to the shaft 11 and the arms of the magnets point outwardly, terminating with integral pole shoes 39 for co-operation with the ends of cores 25. The upper magnet marked *m* is mounted with its pole shoes 39 downturned toward and into close proximity with the upper ends of cores 25. The lower magnet marked *m'* is mounted with its pole shoes 39 upturned toward and into close proximity with the lower ends of cores 25. The arms 38 of the lower magnet *m'* lie directly beneath the arms of the upper magnet *m* but the arrangement is such, as will be clear from a comparison of Figs. 2 and 3, that beneath each pole shoe of magnet *m* is a pole shoe of opposite polarity on the magnet *m'*.

The magnets, as herein shown, each have a central hole therethrough through which a non-

circular section of shaft 11 loosely passes. Matrix metal 40 is cast in each such hole and around the non-circular part of the shaft to hold each magnet thereto. This particular holding means is purely exemplary and the magnetic rotors 5 may be fixed to the shaft in any other suitable way.

The upper section 17 has a horizontal wall 41, having a central opening in which the hollow hub 42 of a timer plate 43 is mounted on ball 10 bearings 44. This mounting enables the timer plate to be shifted angularly relative to shaft 11 for spark timing purposes by any suitable means (not herein shown), in a manner well understood in the art. It will be understood that plate 43 is normally stationary but capable of being angularly shifted for varying the timing of the spark. The upper end of shaft 11 extends loosely through the hollow hub 42 and has fixed thereto a cam 45 for actuating the breaker point 20 mechanism, opening and closing them in proper timed relation with the breaks in the magnetic circuit effected by movement of the magnetic rotors *m* and *m'*. Any suitable breaker point mechanism may be used for the purpose.

An exemplary form of breaker point mechanism is shown in Fig. 5. It includes relatively fixed and movable breaker points 46 and 47, the former being stationarily but adjustably mounted on timer plate 43 and grounded thereto and the latter being fixed to one end of a lever 48 of insulating material pivotally mounted on a stud 49 and having its other end located so as to be engaged by cam 45. A spring 50 serves to move the lever 48 into engagement with the cam and also as an electrical conductor to connect breaker point 47 to a terminal 51, fixed to an insulating block 52 secured to plate 43. A condenser 54 is also mounted on this plate and has one terminal grounded thereto, the other terminal being connected by a metal piece 55 to terminal 51.

A distributor is provided above the timer and comprises a series, eight in this case, of terminals 56, mounted in cap 18 and having sockets 57 to receive the usual spark plug wires (not shown), and a brush 58, fixed to the upper end of shaft 11. The inner end of brush 58 is connected to a terminal 59 in cap 18, such terminal having a socket 60 to receive one end of a high tension wire, the other end of which is received in socket 32 and connected to terminal 33 and thus to the high tension terminals of all the secondary coils.

The electrical connections are shown in Fig. 9. The several primary coils 28 are connected in series and one terminal of one end coil of the series is grounded. The other end coil of the series is connected by a wire 61 to the terminal 51 and thus to the movable breaker point 47 and the insulated terminal of the condenser 54. The primary coils are thus connected in a series circuit which can be opened and closed by the disengagement and engagement, respectively, of the breaker points 46 and 47. The secondary coils as shown, are connected in parallel, one terminal of each being grounded and the other terminal of each being connected, as described, to the terminal 33 in socket 32. The parallel connection of the secondary coils is not however, essential. The various wire connections between the coils may be made within the coil housing, comprising the parts 16, 21, 22, 24, and only the wire 61 and a ground wire need pass outside the housing. The high tension terminal 32 is con-

nected to terminal 59 of the distributer by a wire 62.

The operation of the magneto will next be described. Assuming that the magnets *m* and *m'* have been moved backwardly (clockwise) until they are positioned so that their pole shoes 39 overlie and underlie, respectively, the ends of cores 25, four magnetic circuits are then established,—one through each set of generating coils. For example, flux from each north pole of magnet *m* will flow down through a non-coil-carrying core 25 to a south pole of magnet *m'* and thence from an adjacent north pole of magnet *m'* upwardly through a coil-carrying core 25 to a south pole of magnet *m*. As the rotors turn in a counterclockwise direction, they will eventually assume the positions illustrated in Figs. 2 and 3 in which the magnetic circuits just described, will be broken at four points by air gaps 63 and other magnetic circuits will be established in an opposite direction through each set of generating coils. Thus, flux from each north pole of magnet *m* will now pass downwardly through a coil carrying core 25 to a south pole of magnet *m'* and from an adjacent north pole thereof, flux will pass upwardly through a non-coil-carrying core 25 to a south pole of magnet *m*. Thus, at the moment illustrated in Figs. 2 and 3, a magnetic circuit in one direction through each coil has just been broken and a magnetic circuit in the opposite direction just established,—thus securing a reversal of flux and therefore a large flux change. At this moment, the cam 45 separates the breaker points 46 and 47 and a spark is produced. There will be eight such breaks and flux reversals during each revolution of shaft 11 and the breaker point cam has eight projections to cause an opening of the primary circuit at each of said breaks. It will be noted that the construction affords a compact arrangement of parts. The coils are placed as closely as possible to the drive shaft and for a given size of coil the diameter of the casing is as small as it is feasible to make it in a high tension magneto, where both primary and secondary coils are used. The coils are packed so closely together that no room is available for coils on four of the cores. While these last mentioned four cores might also be equipped with coils, if desired, this would mean an increase in diameter of the magneto casing, with the result that it might be too bulky for the timer-type mounting. The coils constitute the limiting factor here. No difficulty is presented in getting the magnets within the desired space limitations because they are made of special steel,

which by reason of high quality rather than large dimensions, produces all the flux that is needed. The magnets, though small, are of exceedingly high coercive force. The arrangement lends itself to the use of two magnets in series in each of the four magnetic circuits. Some means has to be provided for interconnecting adjacent cores at their lower ends and, while such means might merely be magnetizable material, it is advantageously made of permanently magnetic material because of the added supply of flux thereby secured.

The invention thus affords an exceedingly compact arrangement of parts in a high tension magneto, with all moving parts kept to as low weight as feasible and the heavier parts,—the coils and cores,—located stationarily between the two rotors and packed closely around the shaft.

What I claim is:

1. A magneto, comprising, a driving shaft, a pair of rotors fixed thereto in axially spaced relation and each comprising a plurality of radially extending arms, a stator mounted between the arms of the two rotors and surrounding said shaft, said stator comprising a circular series of cores equal in number to the arms of a rotor, each core mounted in substantially parallel relation with said shaft and having its ends located in inductive relation one with the arms of one rotor and the other with the arms of the other rotor, at least one of said rotors being a permanent magnet with alternate arms of opposite polarity, and coil units mounted one unit on alternate cores of the series and each comprising a primary and a secondary coil.

2. A magneto, comprising, a driving shaft, a pair of rotors fixed thereto in axially spaced relation and each comprising a plurality of radially extending arms, a stator mounted between the arms of the two rotors and surrounding said shaft, said stator comprising a circular series of cores equal in number to the arms of a rotor, each core mounted in substantially parallel relation with said shaft and having its ends located in inductive relation one with the arms of one rotor and the other with the arms of the other rotor, each of said rotors being a permanent magnet with alternate arms of opposite polarity, each arm of one rotor being of opposite polarity to the corresponding and opposed arm of the other rotor, and coil units mounted one on alternate cores of the series and each comprising a primary and a secondary coil.

KENNETH A. HARMON. 55
